UNITED STATES PATENT OFFICE.

WILLIAM H. MUZZY, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER.

1,026,762.

Specification of Letters Patent.

Patented May 21, 1912.

Application filed May 18, 1907. Serial No. 374,426.

To all whom it may concern:

Be it known that I, WILLIAM H. MUZZY, a citizen of the United States, residing at Dayton, in the county of Montgomery and 5 State of Ohio, have invented certain new and useful Improvements in Cash-Registers, of which I declare the following to be a full, clear, and exact description.

This invention relates to improvements in 10 cash registers, and has more particular relation to improvements in machines of the so called multiple drawer type in which an independent drawer or receptacle is provided for each clerk.

15 The object of the invention is to provide improved mechanism whereby the movement of any particular cash receptacle will select its respective clerk's designating element of the register.

20 A further object is to provide means whereby the opening of any one of the clerks' receptacles will bring into operation a motor for operating the register.

With these and incidental objects in view, 25 the invention consists in certain novel features of construction and combinations of parts, the essential elements of which are set forth in appended claims and a preferred form of embodiment of which is 30 hereinafter specifically described with reference to the drawings which accompany and form part of this specification.

Of said drawings: Figure 1 represents a 35 vertical transverse section through the devices embodying the invention, applied to the type of machine shown in Patent No. 580,378, issued April 13th, 1897 to Cleal and Reinhard. Fig. 2 represents an end elevation of the same partly broken away.

40 Fig. 3 represents a similar view taken from the opposite end of the machine. Fig. 4 represents a diagram of the electrical connections. Figs. 5 and 6 represent, respectively, a side elevation and a top plan view 45 of one of the magnetically operated latches. Figs. 7 and 8 represent, respectively, a detail side elevation, and a detail front elevation, of the wiper arm for returning all of the automatic keys to their normal 50 latched positions.

In machines of the type known as mul-

tiple drawer machines it has customarily been the practice to allot a single compartment, or a single cash drawer, to each clerk; and to release this cash drawer, or drawers, 55 by first operating certain elements in connection with the register and then setting in motion the operating mechanism of the register, which, after a predetermined period, would effect the opening or release of 60 the cash receptacle.

It has been customary in machines of this type, to have certain functions of the register proper fully performed before the cash drawer was opened, so that access may 65 be had to the cash therein. The idea of this structure was, that no clerk should have access to his cash drawer to make change until the process of registration was so far advanced that he could take no advantage 70 of a previous registration or indication, and so that there would be no retracting or leaving the subsequent registration in its partially completed state.

In the present invention the cash drawers 75 are unlatched and drawn out by hand, although it will of course be apparent that springs may be inserted behind the cash drawers so that when they are unlatched they will be automatically forced out of the 80 casing. When any one of the drawers is so drawn out of the casing, one of a series of circuits is completed; this circuit releasing the particular clerk's key corresponding to the cash drawer withdrawn and at the same 85 time completing the circuit of an electric motor connected to drive the machine. After this circuit has been once completed by the opening of the drawer, a shunt circuit is closed whereby the closing of the 90 drawer again will not break the circuit until after the motor has made a complete operation.

As many of the details of the present machine are fully shown and described in Letters Patent No. 580,378, no detailed description of the indicating and printing mechanisms will be given, but reference to said patent for such description may be made.

Referring to Fig. 1 in the accompanying 100 drawings, it will be seen that each of the clerks' keys 1 is normally latched in its outer

position by a projection 2, fastened to an armature 3 of a magnet 4, engaging a notch 5 formed in the outer end of each of the keys 1. The clerks' keys, when released, 5 are forced inwardly by springs 6 surrounding said keys, and abutting against pins 7 carried by the keys, and against a plate 8 through which the keys slide. A hood 9 covers the outer ends of the keys and the 10 magnets so as to prevent manipulation of said keys.

The keys 1, when released project into the path of a pawl 16 carried by an arm 16^a pivotally secured to a segment 11 which is 15 loosely mounted upon a rock shaft 12. A cam 13 secured to the rock shaft is arranged to be moved in the direction of the arrow a distance of about 90 degrees upon the beginning of the operation of the machine, and upon its return a shoulder 14 formed upon the cam engages a similar shoulder 15 formed upon a slide 10 supported by the lower ends of two arms 10^a, which are pivoted at their upper ends to the 20 segment 11, and carry said segment with it. An upwardly extending portion of the arm 16^a is bifurcated and straddles a pin 10^b projecting from the slide 10. A spring 16^b is seated in the rear end of the arm 16^a with 25 the free end abutting against a flange 16^c projecting from the segment 11 and thereby forces the shoulder 15 into engagement with the shoulder 14 whenever the latter presents itself. These shoulders are disengaged by 30 the pawl 16 contacting with the inner end of one of the keys 1 which will rock the arm 16^a and thereby move the forward end of the slide 10 into one of the recesses 20^a formed in a plate 20^b and positively lock the segment 11, to which the slide is attached, from 35 further movement.

Fastened to the rock shaft 12 is an arm 17 having pivoted to its outer end a pawl 18, which is free to rock about its pivotal 45 point, against the tension of a coil spring 19, in one direction, but is prevented from moving in the opposite direction by a pin 20 with which the tail 21 of the pawl contacts. This arm and pawl are mounted 50 upon the rock shaft relative to the segment 13, in such a manner that immediately after the shoulders 14 and 15 are disengaged by the pawl 16 contacting with the inner end of a depressed key, the beveled end of the 55 pawl 18 will contact with the pin 22 of the depressed key and force said key outwardly against the tension of its spring until it is latched in its outer position by the projection 2 of the armature 3.

60 As the armature and magnet for each key are similar, a description of one will suffice for all. Referring to Fig. 1 it will be seen that each magnet 4 is suitably supported upon a bracket 23 within the hood 9, and

projecting from the magnet (Figs. 5 and 6) 65 is a pair of uprights 24 equipped with guide fingers 25 extending into cut out portions 26 of the latch projection 2 of the armature 3. The projection 2 is normally forced into engagement with the recess 5, formed in its 70 companion key 1, by a coil spring 27 surrounding said projection, one end of which contacts with a pin 28 while the outer end abuts against the lower guide fingers 25 formed upon the uprights 24. 75

The cash receptacles 28^a, of which there are as many as there are clerks' keys but of which three only are shown, are in the form of drawers and each is provided with a pull 29 secured to its front end. A latch 30 in 80 the form of a bell crank lever is suitably mounted within a cut-out portion 31 of the forward part of each cash drawer. The upper end of the vertical arm of each bell crank is normally forced into a recess 32 of 85 a partition 33 by a leaf spring 34 secured within the cut-out portion 31, so as to prevent the opening of the cash drawer accidentally. The horizontal arm of the bell crank projects forwardly into the pull 29, 90 and is arranged to be raised by the fingers of the operator so as to withdraw the vertical arm from out of the recess 32 against the tension of the spring 34, and thereby allow the withdrawal of the cash drawer. 95

Upon the rear end of each cash drawer is pivotally mounted a spring drawn hook lever 35, the hook end of which, when the cash drawer is in a closed position, engages a pin 36 mounted upon a spring pressed 100 lever 37 pivotally mounted upon the partition 33. The upper end of the lever 37 is provided with a V shaped insulating block 38 which normally holds the contact plates 39 apart. The plates are suitably mounted 105 upon a false back and are connected to binding posts 40. Upon the opening of a cash drawer the hook end of the lever 35 will engage its pin 36 and rock the lever 37 about its fulcrum, against the tension of a spring 110 41. The rocking of the lever 37 will withdraw the block 38 from out of engagement with the spring contact plates 39, allowing them to spring together to close a circuit as hereinafter more fully described. As the 115 cash drawer continues its outward movement the pin 36 will pass below the plane of movement of the hook lever 35 and be released and forced back to normal position by its spring 41. A foot 42 limits the rearward movement of the lever 37. The spring 43 connected to the lever 35 is stronger than the spring 41, so that when the cash drawer is pulled out the lever 35 will not ride over the pin 36 without rocking the lever 37. A 120 foot 44 of the lever 35 abuts against the rear of the cash drawer to limit the downward movement of the lever 35. 125

As shown in Fig. 2, a motor 46 is mounted alongside of the register, and its shaft 47 is provided at one end with a worm 48 which meshes with a worm wheel 49 mounted to 5 rotate upon a shaft 50 suitably secured to the register casing 51. Fastened to the side of the worm wheel 49 is a gear wheel 52, which meshes with a similar wheel 53 rigidly secured to a shaft 54 that extends 10 through the machine. The wheel 53 meshes with another gear wheel 55 fastened to a shaft 56, which also extends through the machine. Attached to the side of the gear wheel 55 is a disk 57 equipped with a shoulder 15 58, which normally engages the end of a pawl 59 pivotally mounted upon the register casing and held in position by a spring 60. The pawl 59 is arranged to be drawn out of engagement with the shoulder 58 by an electric 20 magnet 61, which attracts a soft metal plate 62 attached to the under side of said pawl when said magnet is energized as hereinafter described. The magnet is mounted upon a bracket 63 attached to the register 25 casing 51.

As above described, the shaft 54 extends through the machine and rotates in the direction of the arrow, Fig. 1. Fastened to this shaft 54 is a disk 64 provided with a 30 cut-away portion 65, which as the disk is rotated permits the contact plates 66 to separate and temporarily break the circuit at this point. The contact plates 66 are mounted upon opposite sides of a fiber plate 67 and 35 are provided with binding posts 68.

When any one of the cash receptacles is withdrawn, an electromagnet 69, Fig. 1, is energized and attracts an armature 70 pivotally mounted at 71 against the tension of 40 its spring 72. The rearward end of the armature 70 as it is attracted by the magnet 69, contacts with a conducting strip 73 suitably secured to the register frame, and forms a shunt circuit so that when the lever 37 45 flies back by means of its spring 41 and separates the contact plates 39, the circuit will still be made as hereinafter described.

The differential movement of the segment 11 is transmitted to the clerk's indicator 74 50 by an intermediate gear 75 and a gear 76 secured to said indicator. The intermediate gear 75 is fastened to one end of one of a series of nested sleeves 77 which surround the shaft 56, while the other end, Fig. 3, is provided with a type carrier 78. The extreme left hand end of the shaft 56 has rigidly secured thereto a disk 79 equipped with a cam groove 80, in which plays a pin 81 secured to the side of a platen carrier 82. The configuration of the groove 80 is such that upon 55 a complete rotation of the disk 79, the platen carrier will be reciprocated twice; first to take an impression from the type carrier upon the check which is then cut off and 60

ejected, and second to take a similar impression upon the sales strip 84. It is to be understood that the amount keys 85, Fig. 2, control the indicator and type carrier similarly to the clerks' keys, all of which is fully shown and described in the aforementioned 65 patent.

Referring now to the diagram shown in Fig. 4, the different circuits will be traced. Assuming the upper insulated block 38 shown in said diagram to be withdrawn 70 from between the contact plates 39 by the outward movement of the cash drawer controlling said block, a circuit will be made as follows: from the battery 86, through the wire 87, to the motor 46, wire 88, through the shunt magnet 69, wire 89, lock controlling magnet 61, wire 90; thence through the clerk's key magnet 4, wire 91 to the contact plates 39, through the wire 92 to wire 93, contact plates 66, and through the common 85 return wire 94 to the battery 86. As soon as the above described circuit is made, the magnet 69 will attract the armature 70 and one end of said armature will contact with the strip 73 and thereby shunt the circuit 90 from wire 89 through wire 95 to the armature 70, strip 73, wire 96 to the wire 93, thence through the contact plates 66 to the battery by wire 94. The establishment of this shunt circuit which is of much less resistance reduces the current in the circuit previously traced so greatly as to permit the latching of the plunger 1 by its armature projection 2 and the restoration of pawl 59 to locking position, as magnets 4 and 61 will 100 then be unable to hold their armatures against the force of the restoring springs. The circuits for the remaining drawers will be the same, excepting that the individual wires 91^a and 91^b connect the clerks' key 105 magnets 4 to their respective contact plates 39 located in the rear of the cash drawers, and from the contact plates 39 extend wires 92^a and 92^b to the common wire 93.

Near the end of a rotation of the shaft 110 54 the notch 65, cut in the periphery of the disk 64 secured to said shaft, permits the contact plates 66 to spread apart temporarily and deenergize the shunt magnet 69, the armature of which is drawn out of contact with the strip 73 by the spring 72, the shaft 54 being carried its full movement by the momentum of the moving parts.

The lost motion between the worm 48 and the gear 55, Fig. 2, is such that before 120 this motion is taken up by the motor 46, there is likelihood of the lock controlling pawl 59 returning to lock the wheel 55, by the establishment of the shunt circuit, in which case the gearing would be considerably strained and twisted. In order to prevent this possibility, the following means is provided: Pivoted to the disk 57 is a pawl 97

which is forced into engagement with the rear end of the locking pawl 59 by a light coil spring 98. When the pawl 59 is drawn down by its magnet 61, the pawl 97 passes over its upper side and holds said locking pawl in its unlocking position. The forward movement of the pawl 97 is limited by a pin 99 mounted in the side of the disk 57. When the disk 57 is rotated, the pawl 59 rides upon its periphery, and near the end of rotation of the disk the pawl 59 contacts with the pawl 97 and forces it against the tension of its spring into the position shown in Fig. 2.

15 It will be seen from the foregoing description that, when any one of the cash drawers is drawn outward, the circuit for that particular drawer will be closed by the mechanism located immediately back of the 20 drawer. This closing of the circuit will energize the magnet pertaining to that particular clerk's key, or plunger, which will effect the withdrawal of the latch and permit the key, or plunger, to project down into the 25 path of the latching member carried by the differential segment. By this means the segment will be arrested by the projecting key, in a position bringing the proper indicator and the proper printing type into position. At the time this key circuit is closed, 30 the unlatching magnet is energized which unlocks the machine; and the shunt magnet is also energized which makes a circuit not including the contact points behind the cash 35 drawer so that as the wedge springs back and separates the contact points, the circuit is not broken and the motor continues in operation until its circuit is momentarily broken by the cam disk connected to the 40 rotation shaft as before described.

It will be observed by reference to Fig. 4, that after the shunt circuit is closed all of the key latch magnets, as well as the main machine locking magnet, are ineffective and 45 the key latches are thus permitted to assume their normal latching positions. It will further be seen that the wiper arm follows directly behind the latch of the differential segment in each instance, so that after the 50 latch has been arrested by striking the key, the continued upward movement of the wiper arm will immediately return the key to its normal position, where it will be latched by its armature latch which is made 55 again effective by the completion of the shunt circuit.

With the above devices the first operation of the machine is the opening of a cash drawer, but when any cash drawer is opened 60 the operation of the machine is started and cannot be arrested by the operator. The opening of the cash drawer also determines, or selects, the clerk's key, and this key moves to operating position before the motor gives

the devices sufficient movement to prevent 65 the key from assuming an operative position. It will of course be understood that suitable alarms are controlled by the cash drawers in opening, so that one clerk cannot open the cash drawer of another without 70 detection.

In operating a machine of this type the operator first depresses the proper amount 75 keys; he then takes hold of the drawer pull of his proper cash drawer and with it draws the drawer out far enough to reach the coins in the front coin spaces; he then proceeds to make change, and before he has completed this transaction and closed the cash drawer the machine has completed its operation. 80

Having thus described my invention, what I claim as new and desire to secure by Letters Patent is:

1. In a machine of the class described, the combination with an accounting mechanism, 85 of a series of cash receptacles, and means for operating the accounting mechanism set in operation by the opening of any one of the cash receptacles.

2. In a machine of the class described, 90 the combination with an accounting mechanism, of a series of cash receptacles, means for operating the accounting mechanism and devices controlling the operating means by the initial opening movement of any one of 95 the receptacles.

3. In a machine of the class described, the combination with an accounting mechanism, 100 of a series of cash receptacles, an operating device for the accounting mechanism, means controlled by the opening of any one of the cash receptacles, for setting the operating devices in motion, with provisions for continuing the operation of said devices irrespective of said cash receptacles until the 105 operation is completed.

4. In a machine of the class described, the combination with an accounting mechanism, 110 of a series of department controlling devices, a series of cash receptacles, and means governing the department controlling devices by initial opening movements of the cash receptacles.

5. In a machine of the class described, the combination with a main operating mechanism, 115 of a lock for the same, a series of cash receptacles, and means actuated by the movement of any one of the cash receptacles for operating the lock.

6. In a machine of the class described, the 120 combination with a main operating mechanism, of a series of cash receptacles, a motor for the main operating mechanism, and means for setting the motor in operation by the opening of any one of the cash receptacles. 125

7. In a machine of the class described, the combination with a differentially movable

element, of a series of stop devices controlling the movement of said element, means for normally holding said stop devices in inoperative position, and means for releasing said stop devices and positioning the same for controlling the differentially movable element.

8. In a machine of the class described, the combination with a differentially movable element, of a series of stop devices controlling the movement of said element, means for normally holding said stop devices in inoperative position, means for releasing said stop devices and positioning the same for controlling the differentially movable element, and mechanism for restoring said stop devices to normal inoperative position.

9. In a machine of the class described, the combination with an accounting mechanism, of a series of automatic clerks' keys, a series of cash receptacles, and means for releasing the clerks' keys to permit them to operate by the opening of corresponding receptacles.

10. In a machine of the class described, the combination with an accounting mechanism, of an electric motor for driving the same, a source of electrical energy, a series of cash receptacles, and means controlled by any one of the cash receptacles for completing the circuit through said motor.

11. In a machine of the class described, the combination with an accounting mechanism, of a motor for the same, a lock for said mechanism, magnet controlled setting elements, a series of cash receptacles, connections whereby the opening of any one of the cash receptacles operates the lock for the machine, the motor and the magnet setting elements.

12. In a machine of the class described, the combination with accounting devices, of an electric motor for driving the same, a source of electrical energy, a series of cash receptacles, means for closing the circuit to the motor upon the opening of any one of the cash receptacles, and means controlled by the accounting mechanism for breaking the circuit.

13. In a machine of the class described, the combination with a driving member having a constant movement at each operation of the machine, of a driven member arranged to have a variable movement imparted to it by said driving member, a plurality of cash receptacles, and means controlled by the cash receptacles for governing the extent of movement of the driven member.

14. In a machine of the class described, the combination with a driving member having a constant movement at each operation of the machine, of a driven member arranged to have a variable movement imparted to it by said driving member, an in-

dicator connected to the driven member, a plurality of cash receptacles, and means controlled by the cash receptacles for governing the extent of movement of the driven member.

15. In a machine of the class described, the combination with a driving member having a constant movement at each operation of the machine, of a driven member arranged to have a variable movement imparted to it by said driving member, a type carrier connected to the driven member, a plurality of cash receptacles, and means controlled by the cash receptacles for governing the extent of movement of the driven member.

16. In a machine of the class described, the combination with a driving member having a constant movement at each operation of the machine, of a driven member arranged to have a variable movement imparted to it by said driving member, a series of automatically operating stop elements for controlling the movement of the driven member, and a plurality of cash receptacles for operating the stop elements.

17. In a machine of the class described, the combination with an operating mechanism, of a motor for the same, a source of electrical energy, magnet controlled setting elements, a series of cash receptacles, and means for closing the circuit through the motor and the magnet controlled setting elements upon the opening of any one of the cash receptacles, and then automatically breaking the circuit through the magnets without breaking the motor circuit.

18. In a machine of the class described, the combination with an operating mechanism, of a motor for the same, a source of electrical energy, magnet controlled setting elements, a restoring device for said elements, a series of cash receptacles, and means for closing the circuit through the motor and the magnet controlled setting elements upon the opening of any one of the cash receptacles, and then automatically breaking the circuit through the magnets without breaking the motor circuit, so as to permit the relatching of the setting elements when returned by the restoring device.

19. In a machine of the class described, the combination with an operating mechanism, of a motor for the same, a source of electrical energy, magnet controlled setting elements, a series of cash receptacles, means for closing the circuit through the motor and the magnet controlled setting elements upon the opening of any one of the cash receptacles, and then automatically breaking the circuit through the magnets without breaking the motor circuit, and means controlled by the operating mechanism for finally breaking the motor circuit.

20. In a machine of the class described, the combination with a main operating mechanism, and a locking device therefor, of a cash receptacle, a magnet for operating 65
5 said locking device, a pair of contacts closed by the opening of the cash receptacle and a circuit including said contacts and said magnet.
21. In a machine of the class described, 10 the combination with a main operating mechanism, and a locking device therefor, of a cash receptacle, a magnet controlling said locking device, a pair of contacts, a device moved by said cash receptacle and maintaining said contacts normally separated, and a circuit including said pair of contacts and said magnet. 15
22. In a machine of the class described, 20 the combination with an operating mechanism, of a lock for said mechanism, a plurality of cash receptacles, means controlled by said receptacles for operating the lock, and auxiliary means for holding the lock in an inoperative position. 25
23. In a machine of the class described, the combination with an operating mechanism, of a motor for same, a source of electrical energy, a magnetically controlled lock for the operating mechanism, a plurality of cash receptacles, and means for closing the circuit through the motor and the lock magnet upon the opening of any one of the cash receptacles. 30
24. In a machine of the class described, 35 the combination with an operating mechanism, a motor for same, a source of electrical energy, a magnetically controlled lock for the operating mechanism, a plurality of cash receptacles, and means for closing the circuit through the motor and the lock magnet upon the opening of any one of the cash receptacles, and then automatically breaking the circuit through the lock magnet without breaking the motor circuit. 40
25. In a machine of the class described, 45 the combination with a motor, of a variably movable member driven thereby, and a plurality of cash receptacles for starting the motor and controlling the variable movement 50 of said member.
26. In a machine of the class described, the combination with a motor, of a variably movable member driven thereby, a series of keys for controlling the variable movement 55 of said member, a plurality of cash receptacles for starting the motor and controlling the keys. 60
27. In a machine of the class described, the combination with an accounting mechanism, of a driving motor therefor, a plurality of cash receptacles, and means controlled by any of the latter for starting the motor. 65
28. In a machine of the class described, the combination with an accounting mechanism, of a driving motor therefor, a plurality of cash receptacles, means controlled by any of the latter for starting the motor, and means for automatically stopping the motor after the accounting mechanism has been operated. 70
29. In a machine of the class described, the combination with an accounting mechanism, of a driving motor therefor, a plurality of cash receptacles, means controlled by any of the latter for starting the motor, and means for insuring the complete operation of the accounting mechanism by the motor irrespective of the movements of the cash receptacles. 75
30. In a machine of the class described, the combination with an accounting mechanism, of a driving motor therefor, a plurality of cash receptacles, means controlled by any of the latter for starting the motor, and means controlled by the accounting mechanism for stopping the motor. 80
31. In a machine of the class described, the combination with an accounting mechanism, of means for variably determining the movement of said mechanism, a plurality of cash receptacles, and connections controlled by said cash receptacles for actuating said determining means. 85
32. In a machine of the class described, the combination with an indicating mechanism, and a type carrier, of means for variably determining the movement of both 90 said mechanism and said type carrier, a plurality of cash receptacles, and connections whereby exposure of said receptacles will project said determining means variably. 95
33. In a machine of the class described, the combination with a type carrier, of plunger elements projectible variably to determine the movement of said type carrier, a plurality of cash receptacles, and connections controlled by said receptacles for separately projecting said plunger elements. 100
34. In a machine of the class described, the combination with a type carrier, of plunger elements adjustable variably to determine the movement of said type carrier, magnets controlling said plunger elements, 115 a plurality of cash receptacles, circuit connections for said magnets, and means for changing the electrical condition of said circuit connections by exposure of said receptacles. 120
35. In a machine of the class described, the combination with a differentially movable element, of a series of stop devices constructed to be positioned to control the movement of said element, and a series of cash receptacles corresponding in number to 125 the stop devices and having connections to control the positioning of said stop devices.

36. In a machine of the class described, the combination with an accounting mechanism, of an operating mechanism therefor, a lock for said operating mechanism, and a series of cash receptacles having connections for controlling the operation of both the lock and the operating mechanism.
37. In a machine of the class described, the combination with an accounting mechanism, of a series of cash receptacles, means for operating the accounting mechanism set
- in operation by the movement of any one of the cash receptacles, and devices for maintaining the operating means in operation irrespective of said cash receptacles until 15 the operation is completed.
- In testimony whereof I affix my signature in the presence of two witnesses.
- WILLIAM H. MUZZY.
